ASTRONOMICAL DEVICE

Jerome C. Lafferty, Los Angeles, Calif.

Application February 14, 1944, Serial No. 522,234

4 Claims. (Cl. 35—47)

My invention relates to an astronomical device, and more particularly to a device adapted for illustrating or teaching astronomy.

An important object of my invention is to provide means simulating the starlit sky, in combination with means for adjusting the visibility of portions of same in order that the positions of the stars may be indicated at different times of the year.

Another object of the invention is to provide means of such character that will simulate the sky in the northern hemisphere and also the sky in the southern hemisphere.

Still another object of the invention is to provide adjustable mechanism whereby the means simulating the sky in the southern hemisphere may be turned so that it will be uppermost and most convenient for inspection by astronomy students.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangement of parts, which will more fully appear in the course of the following description. However, the drawing merely shows and the following description merely describes one embodiment of the present invention, which is given by way of illustration or example only.

In the drawing, like reference characters designate similar parts in the several views.

Fig. 1 is an elevation, partly in section, of an embodiment of the foregoing objects.

Fig. 2 is an enlargement, partly in elevation, along the line 2—2 of Fig. 1.

Fig. 3 is an enlarged section, taken along the line 3—3 of Fig. 1.

Fig. 4 is an enlarged, horizontal, broken section, taken along the line 4—4 of Fig. 1.

Fig. 5 is a broken, perspective view of elements comprised in the invention.

Referring more in detail to the drawing, the reference number 6 generally indicates a standard mounted upon a base 7 and having a telescoping section 8. The section 8 is held in its vertically adjusted positions by a set screw 9.

A semi-circular cradle 10 is slidable lengthwise and pivotally held upon the standard section 8 by means of a bolt 12, which in turn is clamped in position by a wing nut 13. Integral with the bolt 12 is a head 14 that has flanges 15 extending

around and frictionally gripping the body member of the cradle 10. The cradle 10 may be slid longitudinally in the gripping flanges 15, to different adjusted positions.

The pivotal movement of the cradle 10 is obtained by unscrewing the nut 13 and swinging the cradle 10 about the bolt 12 as an axis. The nut 13 is thereupon tightened in position to hold the cradle 10 in its new position. If the cradle is swung a full half circle from the position shown in Fig. 1, the southern hemisphere would be uppermost.

The cradle 10 has outwardly extending arms 17 and 18, upon the outer ends of which are pivoted, hollow, hemispherical members 19 and 20 respectively. The dome-shaped members 19 and 20 have bifurcated brackets 21 and 22 approximately at the poles of said members. Bolts 23 and wing nuts 24 hold the domes 19 and 20 in their pivotal, adjusted positions.

Welded to the inner face of the cradle 10 is a bar 25 that substantially bisects the arc described by the cradle 10. The outer end of the bar 25 is connected to a link 26 by an adjusting bolt 27 and wing nut 28. The outer end of the link 26 has a similar adjusting bolt 29 and wing nut 30 that connect the link 26 with an opaque masking board 31. The masking board 31 may carry the letters "N," "W," "E" and "S" to indicate the directions of north, west, east and south, as best shown in Fig. 5. On the inside surfaces of the hemispherical domes 19 and 20 may be indicated stars 32, sun 33, moon 34 and other astronomical phenomena, as desired.

It will be noticed in the drawing that the dome 19 carries the letter "N" on the exterior surface. This is to denote the northern hemisphere, while the dome 20 carries the letter "S" to denote the southern hemisphere.

In practice, my invention has been found to greatly facilitate the understanding of astronomy students in learning the positions of stars, constellations and other astronomical phenomena. In the position shown in Fig. 1, the northern hemispherical sky is shown upward and the southern hemispherical sky is shown downward. It is clear that even without using the masking board 31, astronomy students will be more easily taught by referring to these hollow dome-like hemispheres. Thus it can be seen that the two domes 19 and 20 may be used simultaneously in the position shown in the drawing.

If desired, the positions of the two hemispheres may be reversed by loosening the wing nut 13 and swinging the cradle 10 around until the

positions of the domes are reversed. Then the wing nut 13 is re-tightened in position.

It is believed clear that by loosening the wing nut 28, the masking board 31 may be swung to an inoperative position or be swung to a nesting position in either dome, as suggested in Figs. 1 and 5. A greater or lesser angle may be described by the board 31 by loosening the wing nut 30 and swinging the board pivotally around the bolt 29. The nut 30 may thereafter be tightened to hold the board in its new position. The board 31 has the distinct advantage of cutting off the part of the sky desired to be covered at a certain point in the lecture, or in the use of the device. By adjustment of the board 31, the sky at different seasons of the year and at different points on the earth's surface may be depicted. Either or both of the hemispheres 19 and 20 may, of course, be disconnected from the supporting cradle 10 and held manually with the masking board 31 in the desired position within the hemisphere.

It is to be understood that the masking board 31 is primarily intended as a "horizon piece." In other words, said board establishes the horizon at any desired degree of latitude.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. An astronomical device comprising supporting means mounted to swing about a given axis, hollow, open-ended elements independently arranged upon swinging parts of the supporting means with their open ends facing each other, the inner surfaces of the elements being curved and bearing representations of astronomical phenomena, and a pivotally mounted masking element having a curved surface conforming substantially with the inner surfaces of both of said elements and movable independently pivotally to mask portions of either of said elements.

2. An astronomical device comprising supporting means mounted to swing about a generally horizontal axis, hollow, open-ended elements separately pivotally connected at substantially diametrically opposite positions on the supporting means, the inner surfaces of the elements being curved and bearing representations of astronomical phenomena, an arm substantially bisecting the space between the connections of the elements with the supporting means, and an opaque masking board pivotally mounted on the arm, the board having a curved surface conforming substantially with the inner surfaces of both of said elements and movable pivotally to mask portions thereof, and movable toward and away from said hollow elements respectively.

3. An astronomical device comprising a semi-circular cradle member, supporting means, mechanism on the supporting means to adjustably hold the cradle member with the ends projecting therefrom, the cradle member being longitudinally adjustable in the mechanism, hollow, dome-like elements independently mounted on the outer ends of the cradle member and being pivoted about axes transverse to the plane of said cradle member, the inner surfaces of the elements bearing representations of astronomical phenomena and a masking element also mounted on the cradle member and disposed between the dome-like elements to mask inner face portions thereof.

4. An astronomical device comprising a standard, an arcuately shaped supporting member slidably and pivotally mounted on said standard at a central portion, a pair of spaced semi-spherical elements secured at the ends of said supporting member and being pivoted about axes at right angles to the plane of said supporting member, the inner surfaces of said elements bearing representations of astronomical phenomena, an arm extending radially inward from said central portion, a link pivoted at the end of said arm substantially between said elements, and a masking disc pivoted at the free end of said link adapted to selectively interfit within said elements to mask portions thereof.
